We claim the ornamental design for a display screen or portion thereof with graphical user interface, as shown and described.

CLAIM

The sole FIGURE is a front view of a display screen or portion thereof with graphical user interface showing our new design.

The outer perimeter of the broken line showing of the display screen is for environmental purposes only and forms no part of the claimed design.

The remaining broken lines in the FIGURE depict portions of the graphical user interface which form no part of the claimed design.
